US0D1060161S

(12) **United States Design Patent** (10) Patent No.: **US D1,060,161 S**
(45) Date of Patent: ** Feb. 4, 2025

(54) **PUMP FOR MOTORCYCLE**

(71) Applicant: **Brembo S.p.A.**, Curno (IT)

(72) Inventor: **Ivanoe Maggioni**, Curno (IT)

(73) Assignee: **Brembo S.p.A.**, Bergamo (IT)

(**) Term: **15 Years**

(21) Appl. No.: **35/518,751**

(22) Filed: **Oct. 3, 2023**

(80) **Hague Agreement Data**

Int. Filing Date: **Oct. 3, 2023**

Int. Reg. No.: **DM/232298**

Int. Reg. Date: **Oct. 3, 2023**

Int. Reg. Pub. Date: **Oct. 20, 2023**

(30) **Foreign Application Priority Data**

Apr. 3, 2023 (IT) 402023000000891

(51) **LOC (15) Cl.** **12-16**

(52) **U.S. Cl.**

USPC **D12/179**

LLC

(57) **CLAIM**

The ornamental design for a pump for motorcycle as shown and described.

DESCRIPTION

1.1 : Perspective

1.2 : Back perspective view

1.3 : Left perspective view

1.4 : Right perspective view

1.5 : Front perspective view

1.6 : Back perspective view

1.7 : Bottom

1.8 : Left

1.9 : Bottom perspective view

1.10 : Front

1.11 : Top

1.12 : Back perspective view

1.13 : Bottom

1.14 : Back

2.1 : Perspective

2.2 : Back perspective view

2.3 : Left perspective view

2.4 : Right perspective view

2.5 : Front perspective view

2.6 : Back perspective view

2.7 : Bottom perspective view

2.8 : Right

2.9 : Left

2.10 : Front

2.11 : Top

2.12 : Back perspective view

2.13 : Back

2.14 : Bottom

The broken lines illustrate portions of the pump for motorcycle which form no part of the claimed design.

1 Claim, 16 Drawing Sheets
